UNITED STATES PATENT OFFICE.

JOSEPH E. ZILK, OF PITTSBURGH, PENNSYLVANIA, ASSIGNOR TO ODOLESS FERTILIZER MANUFACTURING COMPANY, OF PITTSBURGH, PENNSYLVANIA, A CORPORATION OF DELAWARE.

PROCESS OF PRODUCING AMMONIA AND POTASSIUM-CONTAINING MATERIAL FROM TOBACCO WASTE.

1,247,060.

Specification of Letters Patent. Patented Nov. 20, 1917.

Application filed February 10, 1917. Serial No. 143,923.

To all whom it may concern:

- Be it known that I, JOSEPH E. ZILK, a citizen of the United States, residing at Pittsburgh, in the county of Allegheny and State of Pennsylvania, have invented new and useful Improvements in Processes of Producing Ammonia and Potassium-Containing Material from Tobacco Waste, of which the following is a specification.
- 10 The present invention relates to a process and an apparatus for treating materials of the nature of tobacco stems and other organic nitrogenous potassium-containing organic matter, for the production of potassium salts, ammonia and other valuable by-products, which potassium salts may be obtained in a relatively pure state if desired, or in the form of a material suitable for use as a fertilizer.
- 15 20 The accompanying drawing shows an apparatus of my invention suitable for carrying out the present process, the view being a sectional elevation.

The apparatus consists essentially of a retort 1 placed above a fire box 2, said retort being provided with an outlet pipe 3 for gases and vapors produced by heating the tobacco waste. The fire box is connected with a flue 5 through which the hot gases are conveyed to a chimney or to the outer air. The pipe 3 leads the gases and vapors to a superheating coil 4, located within the said flue 5, whereby said gases and vapors may be heated to a temperature sufficient to convert a large part of the nitrogenous compounds thereof into ammonia, and whereby numerous other reactions are induced, in the said gases and vapors.

The gases and vapors, after leaving the coil 4, pass by pipe 6 (which constitutes an extension of the pipe 3) to a suitable coil 7, located in a cooled receptacle 8, whereby aqua ammonia (or ammonium carbonate solution) is condensed in said coil, which is separated from the remaining gases in the trap 9. The remaining gases may then pass by pipe 10, to one or more scrubbers 11, where they can be washed with suitable absorbing media for the absorption of the

residual quantity of ammonia, or any other valuable constituents, after which the gases may be delivered into the fire box by pipe 12 and their fuel value thereby utilized. The receptacles 9 and 11 will be provided with suitable draw-off cocks, as shown. The parts 55 10, 11 and 12 may in some instances be omitted.

The retort 1 will be provided with a suitable charging door 13, and the fire box provided with suitable fuel door 14 and draft 60 and ash opening 15, and if desired with a grate 16.

In the carrying out of my process I place in the retort 1, a quantity of the tobacco waste, e. g. stems, stalks, etc., and heat the 65 same to a temperature of about 700-900° F. The gases and vapors given off are then heated, in the coil 4 to a temperature of about 400-500° F. The scrubber 11 may contain sulfuric acid.

In this manner I can convert and recover in the form of ammonia, as much as 12% of the total nitrogen content of the tobacco waste.

The residue in retort 1, may be used directly as fertilizer, alone or mixed with other fertilizer material, upon being leached with hot or cold water gives a solution of potassium carbonate, by evaporation yielding the dry salt, in a condition suitable for 80 use in the arts.

What I claim is:

A process of treating tobacco waste material, said process comprising heating the tobacco waste in the substantial absence of 85 air, to a temperature capable of decomposing the same and of producing vapors and gases and a solid charred residue containing water-soluble potassium compounds, drawing off the vapors and gases and heating the 90 same to convert the major part of the nitrogenous compounds into ammonia, and leading the resulting gases to a condenser wherein the major part of the ammonia is condensed, and separating said condensate from 95 the remaining gases.

In testimony whereof I affix my signature,
JOSEPH E. ZILK.
